UNITED STATES PATENT OFFICE

FREDERICK H. SANDMAN, OF DETROIT, MICHIGAN

FINISHING STRIP

Application filed January 30, 1928. Serial No. 250,445.

The present invention relates to finishing strips for the edges of parts of vehicles and particularly, to a finishing strip or bead adapted to finish the edges of the running boards of automobiles.

Among the objects of the invention is a finishing strip which can be applied to such edges easily and quickly and which will not show at the outside surface any indication of the means by which said strip is secured in place.

Other objects will readily occur to those skilled in the art upon reference to the following description and accompanying drawings, in which:—

Figure 1, is a perspective view of a portion of an automobile and running board showing one use of the material.

Fig. 2 is a section thru a portion of a metal running board showing the strip in place and a method of fastening same.

Fig. 3 is a similar view of a modification applied to a wooden running board.

Fig. 4 is a similar view of a third modification, also applied to a wooden running board.

Fig. 5 is a similar view of a fourth modification, applied to a metal running board.

Fig. 6 is a similar view of a fifth modification applied to a wooden running board.

In the drawing, the body of an automobile is indicated at 10 with a running board at 11 and having fenders 12. It is customary in finishing the running boards of such vehicles to form the board itself, either of wood or sheet metal and cover the surface thereof with some suitable material, such as linoleum 9 or rubber fabric. These materials are put on the boards in any suitable fashion but preferably are cemented in place. After the linoleum or other material has been properly applied, the edge of the running board is usually covered with a metal strip serving to protect the edge of the linoleum and to render the edge of the running board more sightly.

In the present installation, similar running boards are produced, a wooden board being shown at 15 in Figures 3 and 4 and a metal running board being shown at 16 in Figures 2 and 5. In preparing the running board for the use of the present finishing strip, if a

wooden board is used, a groove is cut along its outer edge, such as is indicated at 20 in Figures 3 and 4. After the linoleum 9 or other material has been applied to the board, the finishing strip is applied to the outer edge and nails or screws 21 driven up through the board and through the fastening flange 22.

The finishing strip, as shown, consists of a metal strip having a cross section shaped like the letter F and may have the upper surface 60 of the upper flange provided with a suitable finishing surface, as indicated in Figures 2 and 3 at 23. The flange 22 is located at a point intermediate the stem of the F and may be termed the fastening rib or flange. This strip may be formed in any suitable fashion, but is preferably made of a suitable alloy extruded from a die of the proper shape. It is also contemplated making the strip of sheet metal folded to provide it with a cross section 65 of the same F shape, and this latter form of the device may be suitably coated and used as such, or may be provided with a thin metal cover piece to improve its appearance. Further, instead of forming the stem of the F-shape, straight, as indicated in Figures 2 and 3, it may be somewhat bowed out, as indicated in Figures 4 and 5 at 25.

In case a sheet metal running board is to be used, the board is provided with a depending flange 30, as shown in Figures 2 and 5 and this flange will have a fold 31, intermediate its width, formed to receive the securing flange 22, thus taking the place of the groove 20 in the wooden board. In the case of the metal board, the fold 31 will have its sides perforated at intervals, as indicated at 32 and instead of nails 21, the material of flange 22 may be bumped up into the hole, as indicated at 33, in order to secure the strip in place.

Figure 6 shows a section of a sheet metal finishing strip and in this figure the board 15 is provided with a groove 20, as in Figures 3 and 4.

The finishing strip of Figure 6 is shown as formed of sheet metal in the manner above indicated with the securing flange 42 formed of a fold in the metal of the strip. This folded flange will preferably be perforated, as

at 43, for the reception of nails 21. In this figure, the strip is also shown as being provided with a cover strip 50 secured over the strip by folding its outer edges 51 over the outer edges of the body of the strip.

Now having described the invention and the preferred form of embodiment thereof, it is to be understood that the said invention is to be limited not to the specific details herein set forth and illustrated, but only by the scope of the claims which follow.

I claim:—

1. In combination, a running board provided with a U-shaped groove along its lateral edge intermediate top and bottom thereof and a finishing strip having a flange adapted to enter said groove and be secured therein and having a second flange extending over the edge of the upper surface of said board.
2. In combination, a sheet metal running board for vehicles having an outer depending flange provided with a longitudinal fold intermediate the width of said flange, said fold being open to form a groove and a finishing strip adapted to cover the outer edge of said board and extend over said flange and provided with an intermediate securing flange adapted to enter said groove to be secured therein.
3. In combination, a running board and an F-shaped finishing strip therefor, the top horizontal member of the F overlying the top or tread horizontal surface of the board, the intermediate horizontal member of the F engaging a portion of the board below the top or tread portion, and the vertical member of the F engaging the vertical edge of the board.
4. In combination, a running board and an F-shaped finishing strip therefor, the top horizontal member of the F overlying the top or tread horizontal surface of the board, the intermediate horizontal member of the F engaging a portion of the board below the top or tread portion, and the vertical member of the F engaging the vertical edge of the board, the intermediate portion of the F serving to secure the strip to the board.
5. In combination, a running board and an F-shaped finishing strip therefor, the top horizontal member of the F overlying the top or tread horizontal surface of the board, the intermediate horizontal member of the F engaging a portion of the board below the top or tread portion, and the vertical member of the F engaging the vertical edge of the board, and a finishing strip covering the vertical member and the top horizontal member of the F.
6. In combination, a running board and an F-shaped finishing strip therefor, the top horizontal member of the F overlying the top or tread horizontal surface of the board, the intermediate horizontal member of the F engaging a portion of the board below the top or tread portion, and the vertical member of the

F engaging the vertical edge of the board, the portion of the board engaged by the intermediate member of the F being the walls of a U slot in the board.
